UNITED STATES PATENT OFFICE.

FELIX Q. RAST, OF NEW YORK, N. Y.

DESIGN FOR A VENDING-MACHINE CASING.

60,120.

Specification for Design.

Patented Dec. 27, 1921.

Application filed August 4, 1919. Serial No. 315,328. Term of patent 3½ years.

To all whom it may concern:

Be it known that I, FELIX Q. RAST, a citizen of the United States of America, and resident of the city, county, and State of New York, have invented a certain new, original, and ornamental Design for Vending-Machine Casings, of which the following is a specification, reference being had to the accompanying drawings, forming part thereof.

In the drawings, Figure 1 is an elevation of a vending machine casing embodying the design; and Fig. 2 is a top plan view of the same.

I claim:—

The ornamental design for a vending machine casing, as shown.

FELIX Q. RAST.
